FIG. 2.

၁၂၁

INVENTOR.

BY *Ole Kunk*

his ATTORNEY.

UNITED STATES PATENT OFFICE

2,469,033

REFUSE COLLECTOR

Alexander Thomas Cameron Dear, Hill Top, West Bromwich, England, assignor to Lewin Road Sweepers Limited, West Bromwich, England, a British company

Application May 31, 1946, Serial No. 673,698
In Great Britain May 7, 1946

7 Claims. (Cl. 214—83.32)

1

This invention relates to refuse collectors of the kind comprising a hollow receptacle having at one end an opening for the reception of refuse, feeding means adjacent to said opening adapted to feed the refuse from said opening into the interior of the receptacle and to discharge the refuse therefrom; a shaft extending from said feeding means to the end of said receptacle opposite to the said opening, said shaft and receptacle being rotatable relatively to rotate said feeding means relative to said receptacle and thus feed or discharge the refuse into or out of the receptacle according to the direction of relative rotation.

Usually with refuse collectors of the above kind the receptacle comprises a hollow substantially horizontal cylinder having an opening at one end, the cylinder being mounted for rotation about its longitudinal central axis, the shaft extending along said axis and being supported rotatably from the cylinder, the feeding means comprising a helical screw of a diameter larger than the diameter of the opening and somewhat smaller than the internal diameter of the cylindrical receptacle. Usually the cylinder is mounted upon a chassis which is adapted for road propulsion.

With refuse collectors of the kind hereinbefore specified, the rotation of the feeding means and receptacle relatively serves both to load the refuse into the interior of the receptacle and also to unload the same when required but during such operation refuse of elongated configuration such as wire, rope or string, articles of clothing and so forth, tend to wind around the shaft while this is rotating (relative to the receptacle) and thus elongated objects become tightly wound around the shaft and impede the loading and unloading of the refuse.

The object of this invention is to provide an improved construction of refuse collector of the above kind in which this difficulty is less likely to be encountered than heretofore.

Referring to the drawings—

Figure 1 is a side elevation taken partly in section of a road vehicle embodying a refuse collector constructed in accordance with this invention.

Figures 2 and 3 are enlarged detailed cross section view of the same construction.

In the drawing there is depicted a road vehicle of the general conventional kind including a chassis 10 upon which immediately behind the driving compartment 11 is mounted a hollow body 12 of elongated configuration within which is housed the receptacle 13 which is in the form of

2

an elongated hollow metal cylinder arranged with its central longitudinal axis horizontal and extending parallel to the length of the vehicle.

This cylinder is mounted on the chassis in the known manner for rotation about such axis, being supported therefrom upon a number of rollers indicated diagrammatically at 14, and means, not shown in the drawing are provided for positively rotating the cylindrical receptacle.

The latter is further provided at its rear end with an opening 15 for the reception and discharge of the refuse, which opening has a diameter substantially smaller than the internal diameter of the receptacle, and disposed within the latter a short distance inwardly from the opening is refuse feeding means in the form of a helical screw 16 of known form, the blades 17 of which are in the known manner carried upon a tubular hub 18 affixed rigidly in the known manner to the end of a shaft 19 which extends longitudinally and centrally of the cylindrical receptacle from the forward end 20 thereof opposite to the opening, in which end the shaft is supported rotatably from a bearing 21, and adjacent thereto is adapted to be driven positively and relative to the receptacle from means not shown in the drawing.

The forward end of the receptacle has secured to its inner face a supporting housing 22 of hollow frusto-conical form, the rear end of the housing being of smaller diameter and carrying a bearing 23 which provides a rotatable support for the shaft 19 at a position rearward of the forward end 20 of the receptacle.

The portion of the shaft 19 which extends rearwardly from the bearing 23 is flexible to permit of a certain movement of the feeding means 16 in a direction radially of the shaft axis within the limits imposed by the interior of the receptacle 13 so as to facilitate loading or unloading small solid objects which may otherwise become jammed between the periphery of the blades 17 and the adjacent interior of the receptacle.

The supporting housing 22 and the hollow hub 18 provide housings for those parts of the shaft which they surround and are of an external diameter substantially larger than the diameter of the shaft as will be apparent from Figures 2 and 3 of the drawing, and in accordance with the present invention that part of the shaft which extends between the tubular hub 18 and the housing 22 is enclosed within a sleeve 24 also of an external diameter substantially larger than the diameter of the shaft, the sleeve having the same

external diameter as the tubular hub 18, and the smaller rear end of the housing 22 having the same external diameter as that of the sleeve.

The sleeve is formed of metal of relatively thin section and the length of the sleeve is such that it encloses a substantial proportion of the entire length of the shaft 19.

Each end of the sleeve is secured to the exterior of an annular flange 25 of a bearing 26, the bearing having a central hub 27 rotatably mounted upon the shaft 19 so that the sleeve can rotate freely around the shaft and relative also to the cylindrical receptacle 13.

Each bearing 26 at the end thereof opposite to the flange 25 is formed with an annular groove 28 in which is housed a corresponding packing element 29, the latter engaging the adjacent face of the hub 18 or bearing 23 respectively and thus preventing dust from passing to the bearing hubs 27 while the small gap 30 between each sleeve bearing 26 and the adjacent end of the hub 18 or bearing 23 is covered by the flat-sectioned rings 31 secured one to the rear bearing 26 and the other to the bearing 23.

The sleeve is unsupported from the shaft intermediate its ends so that it interferes to the minimum degree with the radial flexing of the shaft and such flexing is permitted also by the small gaps 30 aforesaid and also by recessing each bearing hub 27 internally for the greater portion of its length as indicated at 32 so that the hubs engage with the shaft 19 over only a small portion of their length.

The cylindrical receptacle 13 is further provided internally in the known manner with a helical rib 33 for the purpose of facilitating the discharge of the refuse when desired through the opening 15 in the known manner.

With the above described arrangement it will be seen that the shaft 19 is completely enclosed within a housing of a diameter substantially larger than the diameter of the shaft and the provision of this larger diameter housing alone reduces appreciably as compared with existing constructions of the above kind the chances of elongated objects becoming wound tightly as aforesaid, while such winding is still further prevented by reason of the fact that part of the housing consists of the sleeve 24 which is mounted for free rotation about the shaft axis and relative to the cylindrical receptacle. Thus if any elongated objects commence to wind around the sleeve 24 they impart a torque thereto causing the sleeve to rotate and prevent further winding.

Although I have described a construction in which only part of the shaft which extends inwardly from the feeding means 16 is enclosed within the rotatable sleeve 24, the remainder being enclosed within the non-rotatable housing 22, it is within the scope of the invention that the rotatable sleeve 24 should extend from the feeding means right up to the forward end 20 of the receptacle, the bearing 23 and tubular supporting housing 22 therefor being omitted.

What I claim then is:

1. In a refuse collector of the kind specified, the provision of a housing enclosing the feeding means shaft, said housing having an external diameter substantially larger than the diameter of the shaft, said housing including a sleeve of corresponding diameter extending for at least a substantial proportion of the length of the shaft, said sleeve extending continuously and completely around said shaft throughout the entire

length of said sleeve, and means supporting said sleeve for free rotation about the axis of the shaft and relative to the receptacle.

2. In a refuse collector of the kind specified, the provision of a housing enclosing the feeding means shaft, said housing having an external diameter substantially larger than the diameter of the shaft, said housing including a sleeve of corresponding diameter extending for at least a substantial proportion of the length of the shaft, said sleeve extending continuously and completely around said shaft throughout the entire length of said sleeve, said sleeve being connected only to said shaft, and bearing means supporting said sleeve rotatably from said shaft so that it can rotate freely around the shaft and relative to said receptacle.

3. In a refuse collector of the kind specified, the provision of a housing enclosing the feeding means shaft, said housing having an external diameter substantially larger than the diameter of the shaft, said housing including a sleeve of corresponding diameter extending inwardly of the receptacle from said feeding means for at least a substantial proportion of the length of the shaft, bearings between the shaft and the two ends of the sleeve supporting said sleeve for free rotation around the shaft and relative to said receptacle, said shaft being flexible and unsupported near the opening of the receptacle, and said bearings engaging the shaft over a very short length thereof.

4. In a refuse collector of the kind specified, the provision of a housing enclosing the feeding means shaft, said housing having an external diameter substantially larger than the diameter of the shaft, a bearing supporting said shaft intermediate the ends thereof, said housing comprising a tubular portion extending between said bearing and the end of the receptacle remote from the opening thereof and attached rigidly to said end, said housing comprising also a sleeve extending between said bearing and said feeding means, said sleeve having an external diameter substantially greater than the diameter of said shaft, and means supporting said sleeve rotatably from said shaft.

5. In a refuse collector of the kind specified, the provision of a housing enclosing the feeding means shaft, said housing having an external diameter substantially larger than the diameter of the shaft, a bearing supporting said shaft intermediate the ends thereof, said housing comprising a tubular portion extending between said bearing and the end of the receptacle remote from the opening thereof and attached rigidly to said end, said housing comprising also a sleeve extending between said bearing and said feeding means, said shaft being flexible and unsupported near the opening of the receptacle, further bearings between the two ends of the sleeve and the shaft, supporting the sleeve rotatably on the shaft, said further bearings engaging the shaft over a very short length thereof and said sleeve having an external diameter substantially greater than the diameter of said shaft.

6. A refuse collector comprising a hollow substantially horizontal cylindrical receptacle having an opening at one end, a helical feeding means mounted for rotation about the longitudinal axis of the cylinder and disposed adjacent to said opening, a rotatable shaft extending from the opposite end of the cylindrical receptacle longitudinally thereof and carrying the feeding means at its free end, a housing enclosing said

shaft, said housing having an external diameter substantially larger than the diameter of the shaft, said housing including a tubular portion secured at one end to the said opposite end of the receptacle and carrying at its upper end a bearing supporting said shaft intermediate the ends thereof, said housing including also a sleeve of corresponding diameter extending from said bearing to said feeding means, a bearing between each end of said sleeve and said shaft, a hub on the end of said shaft carrying said feeding means, said hub having an external diameter corresponding to the external diameter of said sleeve, said shaft being flexible, said sleeve and bearings therefor being spaced slightly at each end and in a direction axially of the shaft from said fixed housing and from said hub, rings mounted on one of these members of a diameter slightly greater than the external diameter of the sleeve extending around each of said spaces.

7. A refuse collector comprising a hollow substantially horizontal cylindrical receptacle having an opening at one end, a helical feeding means mounted for rotation about the longitudinal axis of the cylinder and disposed adjacent to said opening, a rotatable shaft extending from the opposite end of the cylindrical receptacle longitudinally thereof and carrying the feeding means at its free end, a housing enclosing said shaft, said housing having an external diameter

substantially larger than the diameter of the shaft, said housing including a tubular portion secured at one end to the said opposite end of the receptacle and carrying at its upper end a bearing supporting said shaft intermediate the ends thereof, said housing including also a sleeve of corresponding diameter extending from said bearing to said feeding means, said sleeve extending continuously and completely around said shaft throughout the entire length of said sleeve, a bearing between each end of said sleeve and said shaft supporting said sleeve for free rotation around said shaft and relative to said receptacle.
